UNITED STATES PATENT OFFICE.

MAGNUS E. WIDELL, OF CINCINNATI, OHIO, AND FRANK RUDOLPHI, OF MONTCLAIR, NEW JERSEY, ASSIGNORS TO AMERICAN CAN COMPANY, OF NEW YORK, N. Y., A CORPORATION OF NEW JERSEY.

BLANK-SHEARING APPARATUS.

Application filed January 21, 1922. Serial No. 530,776.

This invention relates in general to shearing machines and has more particular reference to an improvement in such machines whereby recovery pieces from the metal sheet being operated upon may be obtained in an efficient and rapid manner.

It is the present custom where automatic machinery is employed in the cutting of a number of articles from a sheet of tin plate, 10 to first sever the sheet into strips by a shearing machine and subsequently to feed the strips so obtained through a press for the cutting of the desired articles. When the resultant article is of a circular configuration it is the common practice to cut such circular disks from adjacent rows of the tin plate in a staggered formation. This permits a more economical cutting of the sheet and provides a minimum amount of wastage. 15

20 In order to make use of an automatic feed in connection with a press cutting the desired articles, it is usually necessary for the strip to contain one row of disk spaces. The strip is so formed as to accommodate the cutting of the round disks in staggered formation by being provided with a scroll or undulating edge which permits the same economy as if the disks were directly cut from the sheets in staggered relation.

30 In the cutting of this staggered strip it is found that spaces occur at the ends of the strip which are not sufficient in size to make a complete disk. It is desirable from the standpoint of economy, and is the customary practice when a condition of this kind occurs, to cut from the spaces left other smaller shapes known in the art as the recovery. The method usually employed for obtaining the final recovery consists in first removing 35 the metal containing the recovery space from the strip and thence feeding the same into a recovery press where the final recovery is cut. To accomplish the removal of the metal strip, a transverse cut is made by a 40 cutting edge offset from the face of and in a plane slightly beneath that of the shearing die. By this method the transverse line across the end of the strip and the shearing line along the edge of the strip are cut at 45 slightly different periods of time with the result that the recovery end is buckled and distorted. It has been found in practice that this distortion seriously interferes with the correct feeding and cutting of the recovery 50

end in a recovery press, and it is toward a removal of this trouble that our present invention is directed.

Our invention contemplates and has for a principal object the economic cutting of the final recovery in the same machine now employed for shearing the strip and permits the recovery to be removed previous to the removal of the metal from the end of the strip. The buckling of the skeleton metal left in the end of the strip after the removal 65 of the recovery is, therefore, of no consequence inasmuch as the metal is discarded as scrap.

Another object of our invention is the provision of an improved method which dispenses with the entire operation at present needed of transferring the strip ends from the shearing machine and feeding the same into a separate recovery press.

Numerous other objects and advantages 75 of the invention will be apparent as it is better understood from the following description, which, taken in connection with the accompanying drawings, discloses a preferred embodiment thereof.

Referring to the drawings, Figure 1 is a vertical section through a shearing press in which our invention is embodied;

Fig. 2 is a plan view, partially in section, 85 taken substantially on the line 2-2 in Fig. 1;

Fig. 3 is an enlarged detail section taken substantially on the line 3-3 in Fig. 2;

Fig. 4 is a plan view of a portion of the metal sheet from which the blanks are formed, showing in outline the form of the main strips and the recovery blanks which are cut out by the press.

Upon the drawings illustrating the invention, the reference numeral 11 indicates a body frame which is supported upon a base 12 and has mounted thereon a table 13 and die members 14 and 15 suitably secured thereto. A shearing die support 16 is mounted for reciprocation in a frame yoke member 17, a dovetail connection indicated at 18 being provided between these parts. Intermittent reciprocation of the member 16 is accomplished by means of crossheads 19 mounted upon vertical rods 21 and secured to a horizontal rod 22 having bear-

ings 23 protruding from a die plate 24 carried by the member 16. The rods 21 are actuated by eccentrics contained in brackets 25 and operated by a power shaft 26, said rod being secured to the actuating members at each end by nuts 27 and 28 respectively. The weight of the die support 16 is counterbalanced by springs 29 carried on rods 31 which are secured by 10 nuts 32 and 33 to the frame yoke member 17. The springs are confined between end disks 34 on the rods 31 and a plate 35 through which said rods extend and which is secured by bolts 36 extending through 15 a downturned extension 37 to a part 38 of the movable mounting for the die support 16.

The blanks are fed in any preferred manner over the table 13 and upon the stationary die parts 14 and 15. In order that the die action may be fully understood, attention is directed first to Fig. 4 in which the reference numeral 41 indicates the outline of the main strips to be cut and the numeral 42 indicates the outline of the recovery which, in the practice of our invention, is removed prior to the action of the dies upon the boundary lines of the main strip in which it is contained. As has heretofore been pointed out, the transverse line 43 has, in certain types of machines, been severed prior to the cutting out of the recovery 42, and in this manner the recovery pieces indicated by the reference numeral 44 have 30 been so distorted as to render difficult the subsequent feeding of such pieces into a press for removal of the recovery. In accordance with our invention the recovery 42 is removed prior to the severance of the line 43 or the boundary lines 45 of the main strip in which the recovery is contained, and this is accomplished by mechanism to be now described.

The die member 14 is provided with an aperture 46 of the form of the recovery and secured in the die plate 24 is a cutting punch 47, adapted to cooperate with the aperture 46 to remove the recoveries indicated in Fig. 3 by the reference numeral 48. Said recoveries or blanks fall into a chute 49 by which they are directed to a trough or receptacle 51 secured in suitable manner to a projection 52 from the frame 11. The sheets to be operated upon, which are designated by the reference numeral 53, are advanced over the table and the lower die members, and the main strips are cut out by the action of a cutting or shearing die 54 secured in the plate 24 and cooperating 50 with the lower fixed die member 15. Said fixed die member is provided with a long aperture 55 of the scroll or undulating form desired, and the die 54 is of corresponding formation and adapted to pass into said aperture as indicated in Fig. 3. The cut

out strips 56 and 57 fall respectively through said aperture and over the outer side of the die member 15 and are both caught in a trough 58 secured to the side of the frame 11. A chute 59 is provided to 70 direct the strips 56 to said trough and together with the chute 49 is fixedly secured at 61 to the die member 14. The apertures 46 and 55 are flared outwardly and enlarged in the lower parts of the die members 14 75 and 15, as indicated at 62 and 63. It will be noted that when the alternate strip spaces 41, which contain the irregular ends from which the recoveries are cut, reach a position beneath the die 54 said recoveries are completely removed leaving blank spaces 64 at the ends of said strips. The die member 15 is provided with bridges 65 and 66 positioned beneath the lines 43 of the strips, the purpose of these bridges being to permit die edges 67, provided in the die 54, to sever said transverse lines 43 so that the entire skeleton, indicated at 69, is removed, leaving a plain short strip, which is designated in Fig. 3 by the reference numeral 56. It will be apparent that any buckling of the metal of the skeleton part 69 through the action of die edges 67 is immaterial since the recovery has already been removed and said skeleton part is merely wastage. Furthermore, the method herein described eliminates the necessity for subsequent operation in another press to remove the recoveries, and a great saving of time and equipment is thus accomplished. 90

The frame yoke members 17 are secured to the table by bolts 71 passing through extensions 72 of said members, and it will be observed that the objects of my invention are effectively accomplished with relatively simple structure involving but slight variation in mechanism and action from the usual type of shearing press.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

We claim:

1. In an apparatus for cutting metal sheets to form blanks from which can ends and the like may be formed, the combination of cutting dies elongated transversely to the direction of the feed of the sheets and having alternating wide and narrow portions for cutting the blanks into transverse strips, the latter containing waste portions, and dies arranged in line with the end portions of the blank-cutting dies and operating in advance thereof at the sides of the sheets for cutting 130

supplemental blanks from said waste portions of said sheets, said advance dies being arranged to be in line with said waste portions only at the moment of cutting.

of main blanking strip-cutting dies having alternating wide and narrow portions and elongated and extending across the line of feed of the sheets, and recovery dies located on the lines of feed of the wastage and operating in timed relation to the main dies, said main cutting dies cutting blanks from a sheet and said recovery dies cutting blanks of different form from parts of the sheets becoming wastage in the action of said blanking dies.

5. 2. In an apparatus for cutting metal sheets to form blanks from which can ends and the like may be formed, the combination of cutting dies having alternating wide and narrow portions for cutting the blanks, and dies arranged in line with the end portions of said cutting dies and operating in advance thereof for cutting supplemental blanks from parts of said sheet which in the action of said first mentioned blanking dies will become wastage, both sets of said dies acting upon the sheet simultaneously and the advance dies only acting on said wastage before the latter arrives at the main cutting dies.

7. In an apparatus for cutting metal sheets to form blanks from which can ends and the like may be formed, the combination of transversely elongated blanking strip-cutting dies having alternating wide and narrow portions for cutting on transverse scroll lines a maximum number of strips from a sheet for the making of can ends and the like, and means associated therewith arranged in advance of said scroll-cutting dies and in line with their end portions for cutting blanks of other configuration from said sheet at points which become the widened ends of said blanks.

8. The process of cutting metal sheets for the formation of can ends and the like, which consists in first cutting relatively small blanks along the side edges of the sheets, and cutting said sheet into scroll like strips, so that alternate strips include the spaces formerly occupied by said relatively small blanks, the cutting of said strips and the cutting of said small blanks being simultaneously performed but at different stations.

9. A method of cutting metal sheets so as to divide them into strip-blanks of scroll-like form and waste portions, in which method formed blanks are cut from said waste portions while the latter are integral with the said sheets and at the same time that the strip-blanks are cut but at different stations.

10. A method of cutting sheet metal blanks which consists in progressively feeding and cutting the sheet into the desired scroll strips and waste portions and, before said waste portions are separated from the sheet, punching smaller shaped blanks from said waste portions, said cutting and punching being performed at the same time but at different stations.

11. In an apparatus for cutting metal sheets to form blanks from which can ends and the like may be cut, the combination with suitable opposing dies, of a scroll die extending transverse to the line of feeding of said sheets, and a punch connected and operating with said scroll die and arranged at the rear thereof in line with an end portion thereof, and acting on successive parts of the sheet before said parts are fed to the scroll die.

12. In the herein described method of cutting strip blanks having alternating wide

6. In an apparatus for cutting metal sheets to form blanks from which can ends and the like may be formed, the combination

65

and narrow portions, and of recovering smaller formed blanks from the ends of alternate strip blanks which consists in removing alternate strip blanks from the metal sheet at a suitable distance from the end of the sheet so that two of said blanks are formed at one cutting, and at each cutting

removing smaller formed blanks along the edges of the sheet, and advancing the sheet with an intermittent movement, each movement being for a distance equal to the width of two of said strip blanks.
